UNITED STATES PATENT OFFICE.

ISADORE J. LANDE, OF BUFFALO, NEW YORK.

LENS GRINDING AND POLISHING MACHINE.

1,201,833.

Specification of Letters Patent.

Patented Oct. 17, 1916.

Application filed January 26, 1914. Serial No. 814,353.

To all whom it may concern:

Be it known that I, ISADORE J. LANDE, a citizen of the United States, residing at Buffalo, in the county of Erie and State of New York, have invented new and useful Improvements in Lens Grinding and Polishing Machines, of which the following is a specification.

This invention relates to a machine for 10 grinding and polishing toric and other lenses having compound curvatures.

In machines as ordinarily constructed, a 15 rotary lens-holder or chuck is employed in connection with a relatively-stationary grinding-pad having its face previously ground or shaped to the desired curvature of the lens. This arrangement requires the use of separate pads for different radii or curvatures, entailing considerable expense. 20 Moreover, if the pad contains imperfections or wears unevenly, which is often the case, the curve imparted to the lens is incorrect or inaccurate.

One of the objects of my invention is the 25 production of a grinding and polishing machine of this character in which the correct grinding of the lenses is not dependent on the perfection of the grinding pad or the accurate curvature of its grinding face, but which 30 is so organized that it will grind lenses to an accurate predetermined curvature or radius regardless of imperfections of the grinding pad and without the necessity of employing numerous pads with different 35 curvatures, thus effecting an important saving.

A further object is the construction of a simple machine of this kind which can be 40 readily adjusted to grind toric lenses to curves of different radii as required.

Another object is to improve the construction of the support or holder of the grinding pad.

In the accompanying drawings: Figure 1 45 is a sectional front elevation of the improved machine, showing the grinding pad in position to grind concave lenses. Fig. 2 is a sectional side elevation of the machine showing the parts in the same position. Fig. 3 is a sectional top plan view thereof. Fig. 4 is a fragmentary front elevation of the machine showing the grinding pad in position to grind convex lenses. Fig. 5 is a 50 face view of the lens-holder or chuck. Figs.

6, 7 and 8 are diagrammatic views illustrating different adjustments of the chuck for producing curvatures of different radii.

Similar characters of reference indicate corresponding parts throughout the several views.

1 indicates the upright frame of a machine on which is mounted a bed or table 2, and 3 is the main driving shaft of the machine journaled horizontally in the frame. Arranged above the table 2 is the rotary work or lens-holder or chuck 4 which is preferably cylindrical, or in the form of a drum, and to the cylindrical rim of which the lens-blanks 5 are adapted to be attached by pitch or any other suitable cement, the blanks being cemented either to the inner or the outer side of the rim to produce concave or convex lenses. In some cases the lens-blanks may be cemented directly to the rim of the chuck, but in grinding concave lenses a number of interchangeable lens-carrying rings of different thicknesses are preferably employed, one of which is shown in the drawings and designated 6. This ring may be removably secured in the 80 chuck by any suitable means.

In the construction shown, the chuck is cast in one piece and its rim is split or divided transversely at diametrically-opposite sides, as shown at 7, the split portions 85 thereof being connected by clamping bolts 8, so that by tightening or loosening these bolts the lens-carrying ring 6 is clamped therein or released. The split portions of the chuck-rim 7 have sufficient elasticity to 90 permit of this action. The chuck is fixed to the front end of a horizontal shaft 9 journaled in a bearing 10 carried by a slide or carriage 11 which is mounted to slide transversely of said shaft on a standard 12. 95 The latter rises from a horizontally-swinging or oscillatory arm 13 arranged above the table 2 and fixed to the upper end of an upright rock shaft 14 which turns in suitable bearings on the table 2 and the frame 1, and extends through and below said table. This shaft is actuated by any suitable means, the preferred means consisting of a rock arm 15 secured to its lower end and having a pin 16 which engages a 100 grooved rotary cam 17 mounted loosely on the main shaft 3. A suitable clutch 18 serves to throw this cam into and out of

gear with said main shaft which is adapted to be driven constantly in the same direction during the operation of the machine. In the construction shown in the drawings, the 5 clutch 18 is shifted by an arm 19 secured to a horizontal rock shaft 20 supported in the lower portion of the frame 1 and provided on the outer side of the frame with a hand lever 21.

10 The chuck carriage 11 may be adjusted on the standard of the oscillating arm 13 by a horizontal screw 22, such as commonly used for adjusting lathe stocks, or by any other suitable means. The carriage is also 15 provided with a set screw 23 for retaining it in position. Rotary motion is imparted from the main shaft 3 to the chuck by a sprocket chain 24 passing around sprocket wheels 25 and 26 secured to the chuck-shaft 9 and the hub of the cam 17. This chain 20 may be provided with a suitable belt tightener 27.

Referring to the concave grinding machine shown in Figs. 1, 2 and 3, 28 indicates the grinding pad mounted in a suitable holder 29 swiveled by a horizontal pivot 30 to the end of a horizontal arm or bracket 31. This bracket extends into the hollow chuck and has a shank 32 arranged at right angles to the axis of the chuck and clamped to the horizontal head of a support or standard 33 by a bolt 34 passing through a longitudinal slot 35 of said shank. By this construction, upon loosening the clamping bolt 34, the pad can be adjusted toward or from the inner face of the chuck-rim to accommodate the same to lens-carrying rings 6 of different thicknesses. To prevent the bracket 31 from swinging laterally on 40 the bolt 34, a pair of clamping screws 34^a bear against opposite edges of the slotted shank, as shown in Fig. 3, these screws being arranged in perforated lugs carried by the standard 33.

45 The pad-supporting standard 33 is pivoted at its lower end to a base-plate or carriage 36 by a pin 37 normally arranged parallel with the axis of the rotary chuck 4, so that said standard may swing at right 50 angles to said axis to permit the grinding pad to approach and recede from the inner face of the chuck-rim. Bearing against the rear side of this standard is a pressure-arm 38 also pivoted at its lower end to the base-plate 36 by a pin 39 arranged parallel with the pin 37 and preferably carrying an anti-friction roller 40 which bears against a boss 41 of the standard 33. This arm carries an overhanging weight 42 whereby a constant 55 pressure is exerted against the standard 33 which in turn presses the grinding pad against the lenses of the chuck, in a manner common to this class of machines. The forward movement of the standard 33 is limited by a suitable stop which preferably 60

consists of a screw 43 bearing against the front side of the standard and adjustably arranged in a standard 44 mounted on the base plate 36.

In order to permit the lens carrying ring 70 6 to be inserted and removed from the rotary chuck 4, it is necessary to withdraw the grinding pad and its bracket 31 from the chuck. For this purpose, the base plate 36 which carries the pad-support 33 is 75 mounted to swing horizontally on an upright pin 45 projecting from the table 2. This base plate may be clamped in position by a vertical screw or bolt 46 journaled in the table 2 and having a handle 47, said 80 plate being provided in its front edge with a notch 48 which receives said screw, as shown by dotted lines in Fig. 3. Other suitable means may however be employed for this purpose. If desired, the hub of the 85 base-plate may be provided with an additional clamping screw 49 which engages the pivot pin 45.

In addition to the pad-support or standard 33, the machine is preferably provided 90 with a supplemental standard 50, of substantially the same construction, arranged to face the outer side of the cylindrical chuck-rim, as best shown in Figs. 1 and 4, to support and hold a grinding pad 28^a for 95 grinding convex lenses. In this case, the pad-bracket 51 is slotted like the bracket 31 and adjustably secured to the top of the standard 50, as in the first described support by clamping bolts 52 and 53, but as 100 the pad is applied to the outer side of the chuck, the bracket is straight and arranged radially of the chuck. The standard 50 is pivoted to swing toward and from the chuck, its lower end being hinged by a pin 105 54 to a fixed base 55 mounted on the table 2. Like the first-described pad support, this supplemental support 50 has a pressure arm 56 carrying an overhanging weight 57, and an adjustable stop 58.

The operation of the machine is as follows: When lenses are to be ground concave, the lens-blanks are cemented to the inner face of a lens-carrying ring 6 of the required thickness to produce a vertical curvature of the prescribed radius. After withdrawing the grinding pad from the chuck, said ring is inserted in the chuck and clamped therein by tightening the bolts 8, after which the grinding pad is returned to 115 its normal position within the chuck, these movements of the pad being effected by swinging the carriage or base plate 36 away from or toward the chuck, as hereinbefore described. Upon now setting the machine 120 in motion, the chuck 4 is constantly rotated on its axis and at the same time bodily oscillated by the rocking movement of the shaft 14 produced by the rotary cam 17. The chuck is thus oscillated on an axis arranged 125 130

substantially at right angles to its own axis of rotation, with the result that this oscillating motion of the chuck in a horizontal plane relatively to the stationary grinding pad causes the lenses to be ground to the desired horizontal curvature, while the rotary motion of the chuck causes them to be ground to the desired vertical curvature. Obviously, the chuck oscillates in a predetermined arc with reference to the face of the grinding pad and the radius of the horizontal curve to which the lens is ground therefore remains constant and accurate, even if the pad has an imperfect surface or develops imperfections by wear.

Variations in the radius of the vertical curve of the lenses are obtained by changing the distance between the axis of the chuck and the face of the lenses. This may be done by using separate lens-carrying rings 6 of different thicknesses, as hereinbefore described, but if desired, the pitch bed in which the lenses are seated may be thinned or thickened for this purpose.

Variations in the horizontal curvature of the lenses are obtained by lengthening or shortening the radius of oscillation of the chuck, or in other words, varying the distance between the axis of the rock shaft 14 and the inner face of the chuck-rim, which is accomplished by shifting the chuck 4 laterally on the standard 12 of the oscillating arm 13 by means of the carriage-adjusting screw 22, the pad-bracket 31 being adjusted accordingly. This action will be clearly understood by reference to Figs. 6, 7 and 8, where the dotted vertical line A indicates the axis of oscillation of the chuck and the dotted line B the distance or radius from said axis to the concave faces of the lenses. In Fig. 6, the axis of rotation of the chuck is coincident with its axis A of oscillation, and in this adjustment the vertical and horizontal curves of the lenses are ground to the same radius, producing spherical lenses. To increase or diminish the radius of the horizontal curvature of the lenses for producing toric lenses, the chuck is shifted laterally to either side of the central position shown in Fig. 6, the chuck being shifted toward the right from said central position to increase said radius, as shown in Fig. 7, and toward the left from said central position to shorten said radius, as shown in Fig. 8. In either case, this adjustment can be readily and accurately effected by means of the carriage-adjusting screw 22. Convex spherical and toric lenses can be likewise ground and polished by adjusting the machine as shown in Fig. 4.

It is a characteristic feature of my invention that the lens-blanks are applied to the circular wall or rim of the cylindrical chuck or lens-holder 4 and that the latter has two motions with reference to the relatively-sta-

tionary grinding pad, viz: a rotary or equivalent motion about its axis and an oscillatory motion on an axis substantially at right angles to its axis of rotation. By this comparatively simple expedient or compound motion of the chuck, the machine is caused to grind both curvatures of toric or other compound lenses with the utmost accuracy, regardless of the shape of the face of the grinding pad or inequalities—of its texture or other imperfections. At the same time, this construction effects an important saving, in that it avoids the necessity of employing a plurality or variety of grinding pads, each having a grinding face of predetermined and previously-ground contour, as in ordinary lens-grinding machines in which one of the two curvatures of toric or other compound-lenses is produced by the curvature of the grinding-pad and therefore depends for its correctness upon the accuracy of the face of the pad and the maintenance of such accuracy throughout the grinding operation of the lens.

I claim as my invention:

1. In a lens-grinding or polishing machine, the combination of a cylindrical lens-holder adapted to carry the lens-blanks on its cylindrical wall, said holder having a compound rotary and oscillatory motion and its axis of oscillation being substantially at right angles to its axis of rotation, means for actuating the holder, and a relatively-stationary grinding pad having its grinding surface arranged to face the cylindrical wall of the lens-holder.

2. In a lens grinding or polishing machine, the combination of a relatively-stationary grinding pad, a rotary cylindrical lens-holder adapted to carry the lens-blank on its cylindrical wall, said holder being mounted to oscillate on an axis substantially at right angles to its axis of rotation and being adjustable transversely of its axis of oscillation to increase or diminish the radius of the lens-curve produced by such oscillatory motion, and means for actuating the lens-holder.

3. In a lens-grinding or polishing machine, the combination of a relatively-stationary grinding pad, an oscillatory member, a carriage adjustable on said member in a plane transversely of its axis of oscillation, a rotary lens-holder mounted on said carriage and co-operating with said pad, said lens-holder having its axis arranged substantially at right angles to said axis of oscillation, and means for actuating said member and the lens-holder.

4. In a lens-grinding or polishing machine, the combination of a relatively-stationary grinding pad, a rock shaft carrying an arm, a carriage adjustable on said arm in a plane transversely of its axis of oscilla-

tion, a rotary lens-holder mounted on said carriage and cooperating with said pad, and means for actuating said rock shaft and the lens-holder.

5. In a lens-grinding or polishing machine, the combination of a relatively-stationary grinding pad, a rock shaft carrying an arm, a cam for actuating said shaft to oscillate said arm, a rotary lens-holder mounted on said arm with its axis substantially
- 10

at right angles to the axis of said rock shaft, and means for actuating said shaft and the lens-holder.

Witness my hand this 24th day of January, 1914.

ISADORE J. LANDE.
